Thomas Carvel, Chauncey, N. Y.

Application August 18, 1955, Serial No. 37,545

Term of patent 14 years

(Cl. D67—2)

FIG. 1

FIG. 3

Fig. 1 is a side elevation of a combination freezer and dispenser showing my new design;

Fig. 2 is a front view thereof; and

Fig. 3 is a top view thereof.

The side of the cabinet which is not shown is substantially like the one shown in Fig. 1, and the back is plain.

I claim:

The ornamental design for a combination freezer and dispenser, as shown and described.
